[57] CLAIM

The ornamental design for an article display stand, as shown and described.

DESCRIPTION

FIG. 1 is a perspective view of an article display stand in accordance with the present invention;

FIG. 2 is a front elevation view of the article display stand shown in FIG. 1; and,

FIG. 3 is a left side elevation view of the article display stand shown in FIG. 1.

The bottom and back of the article display stand form no part of the claimed design. The right side elevation view of the article display stand is a mirror image of FIG. 3. The surfaces within the broken lines shown in FIGS. 1 and 2 are for illustrative purposes only and form no part of the claimed design.
